DECORATIVE STRIPPING

Irving Frohlich, Brooklyn, N. Y., assignor to Assael & Arbib, Incorporated, New York, N. Y., a corporation of New York

Application May 6, 1935, Serial No. 20,001

1 Claim. (Cl. 41—34)

The invention relates to a stripping or similar flexible tape-like binding strip designed to be used as a trimming to be secured to shoes, slippers, belts, handbags, lamp shades and the like, when made of leather, imitation leather, cardboard or fabric, to decorate the same.

The primary object of the invention is to provide an inexpensive form of stripping which can be cheaply and economically manufactured in long strips and which will present a pleasing effect simulating a cloisonne or having some other artistic design showing. In the form of the invention herein selected for specific disclosure the stripping is formed primarily of a layer of paper, tin foil, or celluloid with a design embossed, molded or otherwise formed on its exposed face, and with the exposed design forming face covered with a layer of transparent celluloid preferably colored or tinted celluloid to form a unitary layer of thin, relatively narrow, flexible, all or part celluloid strip permanently secured to a backing or supporting strip.

Various other objects and advantages of the invention will be in part obvious from an inspection of the accompanying drawing and in part will be more fully set forth in the following particular description of one form of strip embodying the invention, and the invention also consists in certain new and novel features of construction and combination of parts hereinafter set forth and claimed.

In the accompanying drawing:

Fig. 1 is a view in perspective of a shoe decorated with lengths of stripping or trimmings constituting a preferred embodiment of the invention;

Fig. 2 is an enlarged view in plan of the stripping shown in Fig. 1 in its flat condition before being applied to the shoe and with parts broken away to show details of construction; and

Fig. 3 is an enlarged transverse sectional view taken on the line 3—3 of Fig. 2 and showing the stripping applied to the leather upper of Fig. 1.

Referring to the drawing, there is shown in Fig. 1 a shoe A provided with an edge binding C and a toe strap D formed of the stripping herein featured and illustrated to show the application thereof to rounded surfaces, in the instant case being the leather upper of the shoe. It is understood that the stripping is made in long lengths and as formed is wound into a spiral flat disc as is usual in marketing tape and similar binding material.

The stripping is formed primarily of a long bottom strip of embossed paper or tin foil 10,

but it is to be understood that it is within the scope of this disclosure to make the strip of celluloid, pyroxlin, cellulose acetate or phenol derivatives of the type usually manufactured in thin sheets. This bottom layer 10 is preferably 5 a sheet of opaque paper, the upper surface of which is colored and which sheet has been embossed to disclose some preformed design such as the heavy wavy lines 11 contrasting with the lighter lines 12 to form an effect simulating a 10 cloisonne or guilloched effect. Positioned on top of the layer 10 is a thin covering layer or coating 13 of transparent and preferably colored celluloid through which the design 11 and its background 12 is visible.

It is within the scope of the disclosure to consider that the layer 10 is a layer of celluloid or equivalent composition material moulded or embossed to provide the desired form of design 11—12 and which in one physical embodiment 20 of the invention is guilloched, as suggested in the Patent to Assael, No. 1,639,716, August 23, 1927, or as otherwise formed to give a cloisonne effect and which effect is visible through the transparent top layer 13 as suggested in the patent 25 to Gloster, No. 1,578,982, March 30, 1926. It is suggested that the strips 10 and 13 be integrally united to form a single strip of composition material, the exposed side 14 of which is polished.

The strip 10—13 irrespective as to how formed is backed by a layer of fabric 15 which underlies the strip 10, laps the edges of the strips 10—13 and overlaps the outer edges of the transparent material 13 to form beads 16 at opposite edges 35 of the stripping leaving the central portion 17 between the beads as an exposed strip through which the design 11—12 is visible. Lines of stitching 18 are passed through the beads and through the layers 10—13 adjacent their longitudinal edges and through the bottom part of the fabric strip 15. The strip is secured to the support D by the use of an adhesive 19. It is within the scope of the disclosure to omit the central part of the bottom strip 15 and thus 45 leave opposite edges of the layer 10—13 protected by the U-shaped binding edge pieces 16.

It is a feature of this disclosure that the stripping can be formed as a long and theoretically endless strip of narrow width and which long 50 strip can be conventionally wound on a feeding spool or itself form a spool which can be rotatably mounted and arranged and fed to the article being decorated in the same manner as ordinary tape is at present applied to a sewing or 55

piping machine. The exposed overlapping or bead forming portion of the fabric backing forming the top side of the stripping can be of a color which combined with the exposed portion 5 of the celluloid strip can provide highly artistic and pleasing appearances. In the instant case, there is provided a three-strip effect when considered longitudinally of the stripping, and which effect is further enhanced by the use of 10 sewing thread which can be of a color contrasting with the color of the fabric 15 and, of course, can be made of a color to harmonize with or contrast with the leather or other material 15 trimmed by the stripping herein featured. In those cases where the sewing is done with a small gauge needle taking a short stitch there is provided the appearance of a line of equally spaced apart dots down each side edge of the stripping which further tends to provide an 20 artistic effect.

In the illustrated embodiment of the invention the stripping has been shown applied as a shoe strap D to illustrate the bending of the stripping about a curved surface with the beaded side uppermost, as the stripping is somewhat 25 more flexible when bent with the fabric side on the inner side of the curve rather than being bent about the beaded side.

While it is suggested herein that the stripping be secured as by cementing to the leather or other surface material being trimmed, it is 30 obviously within the scope of the disclosure to secure the stripping to its support by sewing, by

the use of wire metal fasteners and by the use of other conventional fastening means now known in securing fabric tape to different materials.

While there has been shown, described and 5 pointed out in the annexed claim, certain novel features of the invention, it will be understood that various omissions, substitutions and changes in the form and details of the device illustrated and in its operation may be made by those 10 skilled in the art without departing from the spirit of the invention.

I claim:

A tape-like flexible stripping comprising a long narrow sheet of opaque paper having embossed heavy wavy lines and contrasting lighter lines extending transversely of the length of the stripping, coacting to form an effect simulating a cloisonne design and having its upper embossed surface colored, a thin layer of transparent celluloid superposed thereon and integrally and permanently united to the paper and through which celluloid layer the cloisonne design and its background is visible, the exposed upper surface of the celluloid layer being highly 20 polished, and a fabric backing layer lapping the edges of the paper sheet and celluloid layer and forming protective beads at opposite edges of the stripping leaving the central portion thereof between the beads as an exposed polished face 25 strip.

IRVING FROHLICH.
